UNITED STATES PATENT OFFICE

2,467,138

JEWELRY BOX

Harold A. Lees, Houston, Tex.

Application April 7, 1947, Serial No. 739,919

4 Claims. (Cl. 312—1)

1

This invention relates to display devices for display of articles of merchandise.

An object of this invention is to provide a display means for small articles, such as articles of jewelry, which includes a stand and a receptacle or holder on the stand on which the article or articles to be displayed are placed, the receptacle or holder having a removable cushion so that the color scheme of the window can be easily followed or retained with this display means by mere substitution of a new cushion.

Another object of this invention is to provide a display stand which can be made out of plastic or the like, either colored or transparent, the stand being designed for use as single or multiple units and forming an attractive display means for displaying articles of jewelry to the best advantage.

A further object of this invention is to provide a display stand embodying a base, a standard, a head on the upper end of the standard, and a combined cover and receptacle base slidably and removably engaging the head, the receptacle base also including a removable cushion so that the cushion can be replaced or changed as may be desired.

It is also an object of this invention to provide a display device that may be used as a unit, consisting of a base, pedestal, and box or holder, all connected together, or as a separable device, permitting use of the box or holder separately, and with the box or holder so constructed as to be provided with an inner base that may be slidably withdrawn and separated from the box.

Where plastic is mentioned, it will be understood that the term also includes wood, metal, or other suitable materials.

It has been found that the inventive concept herein expressed provides a merchant, particularly a jeweler, with a very attractive means of displaying his merchandise. The fact that the stands and boxes are in a unitary construction gives them a steady position, and it is easy to trim a window or the like without knocking the boxes over as is the case with ordinary boxes. The invention is also an expense saver as a wide variety of displays and colors is possible without requiring more than a few interchangeable elements of cushions or pads.

With the above and other objects in view, my invention consists in the arrangement, combination and details of construction disclosed in the drawings and specifications, and then more particularly pointed out in the appended claims.

In the drawings,

2

Figure 1 is a detail front elevation of a jewelry box constructed according to an embodiment of this invention.

Figure 2 is a detail side elevation of the device,

Figure 3 is a fragmentary sectional view taken on the line 3—3 of Figure 1,

Figure 4 is a fragmentary sectional view taken on the line 4—4 of Figure 2,

Figure 5 is a plan view of the device, showing 10 the cover in open position and the inner base partly withdrawn,

Figure 6 is a detail front elevation of a modified form of this invention, showing a series of these jewelry boxes or supports on a common base.

15 Referring to the drawings, and first to Figures 1 to 5, the numeral 10 designates generally a base having a vertically disposed standard rising therefrom. The standard 11 has mounted on the upper end thereof a head generally designated as 12, the standard 11 being formed with a threaded stud 13 engaging in a threaded socket 14 which is formed in the bottom plate 15 of the head 12.

The head 12 is formed with opposite side flanges 16 provided with upwardly and inwardly tapered 25 outer sides 17, and the head 12 also includes a front upwardly extending flange 18 which is of curved configuration in plan. The head 12 is adapted to have removably mounted thereon an inner receptacle base 19 which includes a bottom

30 wall 20, opposite side walls 21, a front wall 22 curved to the configuration of the curved front wall 18, and an upright rear wall 23. The inner sides of the flanges 16 and the front flange 18 are formed with a guide groove 24 within which a flange 25, carried by the receptacle base 19, is 35 adapted to slidably engage. The rear wall 23, as shown in Figure 3, extends below the inner bottom wall 20, as indicated at 26, and is adapted to abut against the rear end of the base plate 15 of the head 12.

40 A dome-shaped cover 27 is hingedly mounted at its rear edge, as at 28, at the upper edge of the rear wall 23 and is adapted when the stand is in display position to be swung upwardly to the 45 dotted line position shown in Figure 3.

The inner receptacle 19 is adapted to have removably mounted therein a cushion 29 which includes a cushion body 30 and a cover 31. The cover 31 may be formed of plush or other suitable 50 material of the desired color so that the color of the cover 31 will harmonize with the color scheme used in the complete window display.

As shown in Figures 2 and 3, the side walls of the cover 27 taper forwardly and downwardly and 55 the side walls 16 of the head 12 also taper for-

wardly and downwardly, the smaller end of the side walls 16 being foremost, whereas the smaller end of the cover 27 is rearmost.

Referring now to Figure 6, there is disclosed a slightly modified form of this invention wherein a common elongated base 10a is provided upon which are mounted a plurality of spaced apart vertical standards 11a, 11b, and 11c. The standards 11a, 11b, and 11c, are of progressively greater height with the standard 11c longest, and each standard has mounted on the upper end thereof a head 12a and a closure or cover 27a identical in every respect, with the head and closure and associated parts shown in Figures 1 to 5.

In the use and operation of this device, the article or articles for display are placed on top of the cushion 29 and the cover 27 is raised upwardly to its open position, which is a substantially vertical position, as shown in Figure 3. When it is desired to change the color scheme in the window display, a differently colored cushion 29 may be used so that it will not be necessary for the merchant to completely replace the display stand when changing the color scheme in the window display.

These stands may be made out of any suitable material, preferably being made out of plastic which may be either transparent or colored, and these stands may be used either singly or in multiple units, such as 1, 2, 3, or more standards on a common base. Where the display device is a multiple unit, the standards are preferably of different lengths and may be of increasing height from one end of the base to the other, as shown in Figure 6.

When desired, this device may be used without the standard, as the display holder may be easily removed from the standard.

I do not mean to confine myself to the exact details of construction herein disclosed, but claim all variations falling within the purview of the appended claims.

What I claim is:

1. A display device comprising a base, a standard rising from said base, a lower receptacle base carried by the upper end of said standard, said receptacle base including a bottom wall, upstanding side and front flanges carried by said bottom

wall, said side flanges having confronting channels on the inner side thereof, an inner bottom wall slidably engaging in said channels, a display cushion carried by said inner bottom wall, an upright rear flange carried by said inner bottom wall, and a cover hingedly carried by said rear flange.

5 2. A display device comprising a base, a standard rising from said base, a lower receptacle base carried by the upper end of said standard, said receptacle base including a bottom wall, upstanding side and front flanges carried by said bottom wall, said side flanges having confronting channels on the inner sides thereof, an inner bottom wall slidably engaging in said channels, upstanding inner side and opposite end flanges carried by said inner bottom wall, a cushion removably engaging between said inner side and end flanges, and a dome-shaped cover hingedly carried by the rear inner end flange.

10 3. A display device comprising a base, upstanding side and front flanges carried by said base, said side flanges inclining upwardly and rearwardly and having confronting channels, an inner bottom slidably engaging in said channels, a cushion carried by said inner bottom wall, and a dome-shaped cover hingedly carried by said inner bottom wall.

15 4. A display device comprising a base, upstanding side and front flanges carried by said base, said side flanges inclining upwardly and rearwardly and having confronting channels, an inner bottom slidably engaging in said channels, a cushion carried by said inner bottom wall, a vertically disposed rear wall carried by the rear end of said inner bottom wall, and a cover hingedly carried by said rear wall.

HAROLD A. LEES.
